(57) **CLAIM**

The ornamental design for a plate element for a construction set, as shown and described.

DESCRIPTION

FIG. 1 is a top perspective view of my ornamental design for a plate element for a construction set;
FIG. 2 is a top plan view thereof;
FIG. 3 is a front plan view thereof;
FIG. 4 is right side view thereof;
FIG. 5 is a left side view thereof;
FIG. 6 is a back side view thereof; and,
FIG. 7 is a bottom plan view thereof.
The broken lines in FIG. 7 are for environmental purposes only and form no part of the claimed design.
